(57) **CLAIM**

The ornamental design for a tubular holder for a medical injector, as shown and described.

DESCRIPTION

FIG. 1 is a top, right above perspective view of a tubular holder for a medical injector;

FIG. 2 is a bottom left perspective view thereof;

FIG. 3 is a right above perspective view thereof;

FIG. 4 is a left above perspective view thereof;

FIG. 5 is a left side elevation view, the right side elevation view being a mirror image thereof;

FIG. 6 is a top elevation view, the bottom elevation view being a mirror image thereof;

FIG. 7 is a top plan view thereof; and,

FIG. 8 is a bottom plan view thereof.

The broken lines in the drawings illustrate portions of the tubular holder for a medical injector which forms no part of the claimed design.

1 Claim, 7 Drawing Sheets
